COTTON CLEANER

Arthur C. Moody, Calera, Okla.

Application April 10, 1946, Serial No. 661,161

8 Claims. (Cl. 19—93)

1

This invention relates to new and useful improvements in cotton cleaners.

It is well known that cotton delivered from the field to the gin quite often contains undesired foreign matter, such as stones, sticks, parts of plants, lumps of dirt and the like, which materially affect the ginning operation as well as the quality of the ginned cotton. Such extraneous matter must be removed as completely as possible before the seed cotton is delivered to the gins.

It is therefore one object of the invention to provide an improved cotton cleaner adapted for use in connection with a cotton gin for cleaning and treating the seed cotton prior to delivery to the gin.

An important object of the invention is to provide a cleaner of the character described having improved cleaning surfaces, gratelike in construction, and improved agitators cooperating with said cleaning surfaces, whereby a more efficient cleaning and treating of the cotton is obtained.

A further object of the invention is to provide in a device of the character described improved fan type agitators having a plurality of spaced fingers arranged in staggered relation upon successive blades of the agitator fan so arranged that the paths of the fingers are spaced very closely together as the agitator is turned through a complete revolution, whereby the cotton is thoroughly turned and agitated as it is moved through the cleaner.

Another object of the invention is to provide a cotton cleaner wherein the agitator elements are designed to act as fans and wherein the cleaner housing is provided with openings adjacent the agitators through which air may be drawn by the fan action of the agitators, whereby air currents are set up within the cleaner for agitating and assisting in conveying the cotton therein, and for removing foreign matter therefrom, the cleaner housing also having dampers for regulating the admission of air through said openings.

A particular object of the invention is to provide a cleaner having a grate-like cleaning surface wherein the bars of the grate extend in the line of travel of cotton through the cleaner, whereby progress of such cotton through the cleaner is not retarded by the grate and also whereby the openings in the cleaning surface are sufficiently large to permit large foreign matter to drop readily through the openings in such surface to facilitate the cleaning operation.

A still further object of the invention is to pro-

2

vide a cleaner of the character described which is provided with a manifold for delivering heated air to the cotton being cleaned for drying or treating said cotton as it is cleaned, whereby the cotton is both cleaned and conditioned ready for ginning upon passing through the cleaner.

Still another object of the invention is to provide means for clearing the agitator blades of cotton lint to prevent accumulations on said blades from interfering with the fan action thereof.

A construction designed to carry out the invention will be hereinafter described together with other features of the invention.

15 The invention will be more readily understood from a reading of the following specification and by reference to the accompanying drawings, wherein an example of the invention is shown, and wherein:

20 Fig. 1 is an isometric view of a cotton cleaner embodying the features of the invention,

Fig. 2 is a longitudinal vertical sectional view of the cleaner,

Fig. 3 is an enlarged, transverse vertical sectional view taken along the axis of one of the agitators, and

Fig. 4 is an enlarged fragmentary view illustrating the brushes which clean the agitator blades.

30 In the drawings, the numeral 10 designates generally the cleaning apparatus, having at one end thereof a vertical chute A through which seed cotton is passed as it is conveyed to the cotton gins (not shown).

35 The cleaning apparatus includes a housing B which is in substantially the form of a parallelopiped extending outwardly and downwardly at an angle with the chute, as clearly shown in Fig. 2. The chute A terminates in an inclined bottom

40 plate 11 contiguous to an opening 12 in the end wall of the housing B. The housing is provided with a longitudinal duct 13 in its upper portion, which is separated by a partition 13a from a cleaning chamber 14 which occupies the lower portion of the housing. A vertical duct C extends adjacent the opposite end of the housing to receive cleaned cotton therefrom and has its upper end communicating with the opposite end of the duct 13.

45 A series of rotating agitators 15 which may be of any desirable diameter, are mounted on shafts 16 which extend transversely across the cleaning chamber and have their ends journaled in bearings 17 mounted in longitudinally extending supporting bars 18 provided at the sides of

50

the housing. The shafts are turned by means of pulleys 19 driven by belts 20 from a suitable source of power (not shown). Although three agitators are shown, any desirable number may be utilized.

Each agitator is formed by a plurality of star-wheels 21 mounted in spaced relationship on the shafts and having elongate fan blades 22 mounted at the ends of the spokes of the star-wheels and extending parallel to the shaft. A plurality of agitator fingers 23 are mounted in spaced relationship on each blade of the agitator in such a manner that the fingers on each blade are offset or staggered from the fingers on each of the other blades, whereby the paths of the fingers are spaced, but are close together, as the agitator is rotated. It is preferable that the fingers on each blade be so located on the blade that they move in a path lying between the path of the corresponding finger on the blade moving just in advance and the path of the corresponding finger on the next successive blade, whereby the fingers on successive blades strike the cotton being cleaned or treated at a series of successive points transversely of the chamber, with the result that the cotton is constantly agitated or rolled at different points as the agitator is rotated.

The bottom or cleaning surface of the cleaning chamber is formed of a plurality of spaced arcuate bars or straps 24 having their ends bent around transverse rods 25 which are suitably fastened at each end to the side walls of the housing. The rods 25 are so positioned, and the arcuate bars 24 are so curved, that the bars form concave grate-like cleaning surfaces conforming in general to the arc of rotation of the fingers of the agitators and so arranged that the fingers sweep just above the concave cleaning surface. The grate bars 24 disposed under each agitator are secured at each end to the rods 25 between the ends of the bars of the next adjacent concave section of the cleaning surface, whereby said bars are spaced apart to provide elongate grate openings extending longitudinally of the housing and through which extraneous matter and debris separated from the seed cotton may drop to a trash hopper 26 disposed below the cleaning chamber.

Cross bars 27 having their ends secured to the housing side walls are located at a plurality of points along each of the concave cleaning surface sections for supporting the grate bars 24. Each cross bar has an elongate brush 28 secured to one side of said bar with its bristles extending through the openings between the grate bars so as to engage and shake and tumble the cotton as it passes over said brushes. This agitates and turns the cotton so as to remove more thoroughly the dirt and foreign matter contained therein. Side brushes 29, secured by means of bolts 30 to the side walls of the cleaner housing, are so positioned that they engage and brush off the ends of the agitator blades to prevent lint from accumulating thereon and interfering with the fan action of said blades. The arrangement of the brushes is clearly illustrated in Fig. 4, which is a fragmentary view of the end of one of the agitator blades and one of the cross bars.

Air inlet openings 31 are provided in the side walls of the housing at each end of each agitator for admitting air to the interior of the housing, and as the agitators are rotated the blades act as fans to draw air inwardly through these openings to agitate and clean the cotton, and to as-

sist in the movement of such cotton through the cleaner. The air currents set up by these blades also aid in keeping the blades and agitators free of lint. Damper covers 32 for the openings are pivotally secured to the housing for regulating the size of the opening to control the admission of air therethrough to the interior of the cleaner, said air passing from the housing between the grate bars along with the dirt and foreign matter removed from the cotton.

A hot air conduit 33 having a butterfly damper valve 34 mounted therein is formed with a crosshead 35 providing communication with manifolds 36 at each side of the housing. The manifolds communicate with the openings 31 at each end of two of the agitators to supply hot air from the conduit to the interior of the cleaner at these agitators for drying or otherwise treating the cotton passing through the cleaner. Openings 37 in the manifolds provide for the supplying of cold air to the agitators, if desired, or for regulating the heat mixture of the air delivered through the manifolds to the agitators. Slide covers 38 may be used to close or adjust the size of the openings 37, as desired.

To provide for by-passing the cleaner when the seed cotton does not need cleaning or treating, a flap valve 41 is pivoted at one edge on a pin 42 mounted in the cleaner housing adjacent the intersection of the partition 13a with the vertical chute A, as clearly shown in Fig. 2. Should it be desired not to admit cotton to the cleaner, the valve 41 is swung clockwise to open the mouth of the duct 13 and close the entrance into the cleaner, to permit the cotton to be directed through the duct 13 to the duct C and thence to the gins. However, should it be desired to treat or clean the cotton, the valve is turned to the position illustrated in Fig. 2, whereby the cotton drops to the inclined bottom 41 and is directed through the opening 42 into the cleaning chamber 14.

In use, the cotton is permitted to drop downwardly in the chute A until it engages the inclined bottom 41, whereupon it is deflected into the cleaning chamber, and is directed between the agitators 15 and the grate bars 24. The agitators are rotated in a clockwise direction as viewed in Fig. 2, and the cotton is engaged by the fingers 23 to dislodge any foreign matter therefrom. Since the paths of the fingers are relatively close together, substantially all of the mass of cotton within the cleaner is engaged by one or more of the agitator fingers. It is preferable, however, that the spacing between the fingers upon the first agitator be slightly greater than that of the second and third agitators, so that the cotton is progressively more thoroughly agitated and worked by the fingers as it moves through the cleaner. Dirt, debris and other extraneous matter dislodged from the cotton as it is agitated will be carried by the air currents through the longitudinal spaces between the grate bars 24 into the waste hopper 26, from which it may be removed in any suitable manner.

Movement of the cotton through the cleaner is resisted to some extent by the concave cleaning sections, most clearly illustrated in Fig. 2. However, the blades of the agitators act as a fan to draw air inwardly through the air inlet openings 31, and this air agitates the cotton in the cleaner and assists the fingers in moving said cotton through said cleaner. The cotton is

moved successively past each of the agitators to an outlet opening 43 at the lower or left-hand end of the cleaning chamber, through which it drops into the duct C for delivery to the gins (not shown).

A cylindrical doffer brush 44 having its rows of bristles 45 spaced from one another, is rotatably mounted in the left-hand end wall, and is rotated in a clockwise direction by suitable driving means (not shown). The brush 44 is positioned in the upper portion of the outlet opening 43 so as to provide space below the brush for the egress of cotton, and has its periphery contiguous to the path of the fingers 23 of the left-hand agitator 15. The engagement of the fingers by the brush removes or doffs lint therefrom and the lint is passed out through the opening 43 to the duct C by the brush as it continues its rotation. The brush is of the self-cleaning variety and lint does not accumulate thereon.

Should it be desired to direct heated air into the cleaner for drying or otherwise treating the cotton being cleaned, the butterfly valve 34 in the hot air conduit is opened and the heated air may then flow through the crosshead, the manifolds and the openings 31 to the interior of the cleaner chamber at the two agitators with which the manifold communicates. Of course, cold air may be admitted through the manifold by opening the slide cover 38 which normally closes the openings 37 formed in the manifold. The quantity of cold air admitted through the air inlet openings 31 at the third agitator may be regulated by adjusting the pivoted damper covers 32 which are arranged to close said openings. Obviously, if desired, the hot air conduit and its associated parts may be omitted, or may be connected with only one of the agitators, or with any number of the agitators.

Since the grate bars extend in the line of movement of the cotton through the cleaner, it will be seen that they and the spaces between them do not offer material resistance to the passage of the cotton through the cleaner. Also, the spaces between the grate bars are adapted to permit dislodged extraneous matter to drop readily therethrough to the trash hopper. Such results are great improvements over cleaning surfaces made of screens, or foraminous or perforated material, and the cotton is not materially damaged in cleaning as it passes over this grate-like cleaning surface. The diameters and spacing of the grate bars may be varied to provide greater or lesser openings in the grate-like surface to accommodate cotton of different types, grades and staple lengths.

It is also particularly pointed out that the cleaner does not rely upon an extraneous source of suction or blast to move the cotton into or through the cleaner. Instead, the agitator blades act as fans to draw air into the cleaner and blow it therethrough to agitate the cotton and assist in the movement of such cotton through the cleaner. It is further to be noted that the cotton is delivered to and leaves the cleaner by gravity.

Furthermore, it will be seen that an improved agitator has been provided wherein a plurality of successively staggered fingers on the agitator thoroughly engage, turn and agitate the cotton as it is moved through the cleaner, whereby a more effective treating of the cotton is obtained.

The foregoing description of the invention is explanatory thereof and various changes in the size, shape and materials, as well as in the details of the illustrated construction may be made,

within the scope of the appended claims, without departing from the spirit of the invention.

What I claim and desire to secure by Letters Patent is:

5. 1. A cotton cleaning device including, an enclosed housing having a cleaning chamber therein and an inlet to said housing and an outlet from said chamber, means for conducting cotton from said inlet to said chamber, a cleaning surface bottom for the chamber inclined downwardly from the inlet to the outlet of the chamber and formed of a plurality of elongate curved grate bars spaced apart to provide longitudinally extending openings between said bars, an agitator rotatable in the chamber and having a plurality of elongate agitator blades spaced about its periphery and extending transversely with respect to the grate bars, agitator fingers carried by said blades and spaced with respect to each other so as to move in separate paths as the agitator is rotated, said fingers sweeping close to the grate bars in planes longitudinally of the grate bars to engage and agitate the cotton passing through the cleaning chamber on said grate bars, the housing having inlet openings formed therein at the ends of the agitator, the agitator blades acting as a fan to draw air inwardly through the inlet openings to the chamber for agitating and moving the cotton through said chamber, and means for regulating the admission of air through the openings.

2. In a cotton cleaning device, a rotatable agitator including, an elongate shaft adapted to be rotatably mounted in a cleaner, a plurality of blade supporting members mounted on said shaft, a plurality of elongate agitator blades carried by said supporting members spaced from the shaft and extending parallel thereto, said blades being rectangular in outline and having their width extending radially with respect to the shaft, the inner corner at each end of each blade being cut away to form a beveled portion on said blade whereby the fan action of the blade is enhanced, and spaced agitator fingers carried by each agitator blade.

3. A cotton cleaning device as set forth in claim 1, and brushes extending across the cleaning surface bottom having bristles extending into the openings between the grate bars in close proximity with the paths of rotation of the agitator fingers.

4. A cotton cleaning device as set forth in claim 1, and brushes in the housing in close proximity with the paths of rotation of the ends of the agitator blades for cleaning said ends of the blades as the latter are rotated.

5. A cotton cleaning device as set forth in claim 1, wherein the inner corner at each end of each agitator blade is cut away to form a beveled portion on said blade, and brushes in the housing in close proximity with the paths of rotation of the ends of the agitator blades and with the paths of rotation of the beveled portions of the blades for cleaning the same as the blades are rotated.

6. A cotton cleaning device as set forth in claim 1, and brushes extending across the cleaning surface bottom at each end of those openings between the grate bars immediately below the agitator, said brushes having bristles extending into the openings between the grate bars in close proximity with the paths of rotation of the agitator fingers.

7. A cotton cleaning device including, an enclosed housing having a cleaning chamber there-

in and an inlet to said housing and an outlet from said chamber, means for conducting cotton from said inlet to said chamber, a cleaning surface bottom for the chamber inclined downwardly from the inlet to the outlet of the chamber and formed of a plurality of elongate curved grate bars spaced apart to provide longitudinally extending openings between said bars, a plurality of agitators rotatable in the chamber, each having a plurality of elongate agitator blades spaced about its periphery and extending transversely with respect to the grate bars, agitator fingers carried by said blades and spaced with respect to each other so as to move in separate paths as the agitators are rotated, said fingers sweeping close to the grate bars in planes longitudinally of the grate bars to engage and agitate the cotton passing through the cleaning chamber on said grate bars, the housing having inlet openings formed therein at the ends of the agitators, the agitator blades acting as a fan to draw air inwardly through the inlet openings to the chamber for agitating and moving the cotton through said chamber, and means for regulating the admission of air through the openings.

8. A cotton cleaning device as set forth in claim 7, and an air inlet manifold enclosing the inlet

openings of the first two agitators closest the housing inlet.
